UNITED STATES PATENT OFFICE.

OTTO P. LEINHAUSER, OF SHARON HILL, PENNSYLVANIA.

PUNCH.

1,279,886.

Specification of Letters Patent. Patented Sept. 24, 1918.

Application filed June 1, 1917. Serial No. 172,196.

To all whom it may concern:

Be it known that I, OTTO P. LEINHAUSER, citizen of the United States, residing at Sharon Hill, Delaware county, Pennsylvania, have invented certain new and useful Improvements in Punches, of which the following is a specification, reference being had therein to the accompanying drawings.

The invention relates to improvements in power punches, and more particularly to the releasing and disengaging mechanism for the punch action.

The principal object of the invention is to provide a positive means for withdrawing the punch and punch stock from the work upon the up-stroke of the punch head to provide a positive means for disengaging the block from over the punch stock and to prevent the punch from punching more than a single opening until actuated by the operator.

With the above and other objects in view the invention consists in the certain new and useful construction and arrangement of parts as will be hereinafter more fully described, set forth in the appended claims, and illustrated in the accompanying drawings, in which:

Figure 1 is a front elevation of a punching machine with the releasing mechanism applied thereto.

Fig. 2 is a side elevation of the same, fragmentary in part, and,

Fig. 3 is a perspective view of the punch stock, the actuating block, and the stripper mechanism in detail.

Referring to the drawing, in which similar characters of reference designate corresponding parts in the several views thereof, 1 indicates the punch frame having journaled therein the punch shaft 2. The punch head is designated by the numeral 3, and is vertically slidably mounted in the frame. This head is reciprocated upon the rotation of the shaft aforesaid.

A bracket 4 is formed on the upper end of the frame 1, and pivoted in the said bracket is a lever 5 provided at one end with a counter-balance weight 6 and at its other end with a spring 7, the lower end of which is connected to the punch head, as is clearly shown in Fig. 1. A bracket arm 8 extends laterally from the head 3, and is apertured near its outer end to receive the plunger rod,

21 the latter, and its purpose, to be herein- 55 after more fully described.

Secured to the lower end of the frame 1 are the clips 9 in which are engaged the upper ends of the coiled springs 10, the latter extending downwardly and supporting a horizontally disposed plate 11 upon which is supported the punch stock 12 in line with the head 3, so as to be actuated by the latter in its downward movement. A notch 13 is formed in the punch stock 12, and the use of 65 the same will be obvious as the description proceeds.

Secured to the face plate of the punch is a bracket 14 in which is pivotally supported a rocker arm 15 having one of its ends 70 curved downwardly and provided with a roller 16 adapted to engage the cam 17, which is carried by a wheel 18 mounted on the punch shaft 2. This wheel is provided about its periphery with openings 18^a as 75 seen best in Fig. 2, for the reception of a rod or other implement, whereby the wheel may be turned by hand as desired, to actuate the punch. It will be understood that should it be so desired the cam may be at 80 attached directly to the punch shaft without departing from the spirit and scope of this invention. The end of the rocker arm 15, opposite to that carrying the roller 16, is bifurcated, as illustrated in Fig. 2, to receive 85 a plunger rod, which is to be hereinafter set forth. A retractile coiled spring 18^b is attached to the lever arm 15 near its bifurcated end, and to a suitable bracket support 19 by means of which said spring is 90 held under tension. 20 are adjustable bearing members movable with the plunger rod 21 and adapted to engage the under faces of the bifurcated end of the lever arm 15 as seen clearly in Fig. 2. 95

Slidably mounted in the bracket arm 8, hereinbefore described, is a plunger rod 21, the upper end of which is provided with a set collar 22. Surrounding the upper end of the rod 21 is a compression coiled spring 100 23, which is confined between the upper face of the bracket arm 8 and the set collar 22. It will be seen that the rod 21 is yieldingly held upwardly, so that the rocker arm 15, through the medium of the contact between 105 the bearing elements or members 20, with the under faces of the bifurcations of the rocker arm 15, will normally remain in sub-

stantially horizontal position. A set collar 24 is adjustably mounted on the plunger rod 21, and carries the bearing members 20 aforesaid, through the medium of which the 5 rod 21 is forced downwardly, against the tension of the spring 23, when the lever arm 15 is actuated by the cam 17 to face the bifurcated end of said lever down. A collar 25 is adjustably secured on the plunger 10 rod 21, adjacent the lower end of the latter, and is provided with a lug 26^x adapted for coöperation with an electrically actuated latch 40 controlled by the member 26, the latter being in the form of a solenoid, and 15 whose operation will be hereinafter explained. A bearing bracket 27 is attached to the face plate of the punch and has journaled therein a rock shaft 28 one end of which is in a bearing 29 in the bracket 30. 20 An arm 31 is attached to one end of the shaft 28 and is pivotally connected to the plunger rod 21 while the opposite end of the shaft 28 carries a bifurcated lever 32 which is pivotally and slidably connected to 25 the head 33, of a bolt 34, which is threaded into the block 35. For this purpose the head 33 is provided with the vertical slot 33^x as clearly seen in Figs. 2 and 3. Depending from the bolt 34 is a tongue or bar 36 30 for supporting the stem portion of a stripper member 37, the latter having a beveled end 38, which is adapted to be moved into and out of engagement with the notch 13, formed in the punch stock 12, and when engaged therein, is to be positively actuated for withdrawing the punch from the work during the upward movement of the head. The member 37 is mounted for endwise movement through its opening in the tongue 35 or bar 36, and about said member, is a coil 40 spring 37^x, see Figs. 2 and 3, which is disposed between the adjacent faces of the tongue or bar 36 and the shoulder 38^x of the beveled end 38 of the stripping member. 45 With the parts constructed and arranged substantially as hereinbefore described, the operation, briefly stated is as follows: Normally the block 35 is removed from over the punch stock 12 to prevent the machine from punching. 50 When ready for operation the operator presses a push button 39 electrically connected with the solenoid 26 which completes an electric circuit, energizing the solenoid 55 26 and withdrawing the latch 40 from contact with the lug 26^x, on the collar 25 carried by the plunger rod 21. As soon as this is done the spring 23 acting upon the collar 22 lifts the plunger rod 21 raising 60 the end of the arm 31 which is pivotally connected with said rod, thus actuating the rock shaft 28 so as to throw the lower end of lever 32 to the right in Fig. 2, carrying with it the block 35, the tongue or 65 bar 36 moving with said lever 32 and the block 35, but the stripper member 37 does not at this time move, but the bar 36 slides upon said member 37, compressing the spring 37^x until the block 35 has moved its full distance, into position over the punch 70 stock, the bar 36 contacting with the adjacent head 3. Then the spring 37^x forces the beveled end 38 into the notch 13 of the punch stock 12. When the parts assume this position the 75 head 3 and punch stock 12 descend to punch the material, the parts being properly timed in their action. The springs 10 are distended. Further revolution of the shaft 2 causes the cam 17 which is properly timed 80 in its action to engage the roller 16 raising the same and consequently the adjacent portion of the lever arm 15 and forcing the other end downward against the tension of the spring 18^x so that the bifurcated end of 85 the lever arm engaging the members 20 forces the plunger rod downward. When the cam 17 has moved upward to the point where it engages the rollers 16 the 90 punch has been withdrawn from the material by the upward movement of the head and the downward movement of the plunger rod causes the lever 32 to move outward and withdraw the block 35 from over the punch stock 12. 95 When the tongue or bar 36 has moved outward sufficiently to engage the nut 38^x it pulls the beveled end 38 of the stripper out of engagement with the notch 13 of the punch stock 12 and the parts are in position for another set of operations. 100 It will be evident that the outward movement of the block 35 brings the same out of alignment with the punch stock 12, so that the latter may move upwardly, and the 105 stripper 38 serves as an automatic means for removing the punch from the hole in the material, the said stripper being automatically withdrawn from engagement with the notch 13 of the punch stock 12. 110 It will be understood that the gag block 35, the bar 36 and the stripper members 37, 38 move upward with the head, the slot 33^x in the head 33 of the bolt 34 permitting this movement. 115 The head 3 is of the "floating" type, being reciprocated back and forth continually in a well-known way and by any suitable form of eccentric and coöoperating parts on the shaft 2, which it is not thought necessary to illustrate or to describe in detail. 120 Having thus fully described the invention, what is claimed is: 1. In a punch, a notched punch stock, a punch head associated therewith, a gag 125 movable over the punch stock, a stripper movable with said gag and adapted for engagement with the notch in said punch stock, a rocker shaft, an arm carried by said rocker shaft and having pivotal and 130

sliding movement with the stripper, means for controlling the movement of said rocker shaft and means whereby the gag moves for a portion of its movement independently of 5 the stripper.

2. In a punch action, a notched punch stock, a punch head associated with said punch stock, a gag, a stripper movable with said gag and adapted for engagement with 10 the notch in said punch stock, a rocker shaft, an arm carried by said rocker shaft and connecting said stripper for actuating the latter during the movement of said rocker shaft, a plunger rod for imparting 15 a rocking movement to said rocker shaft, and means for controlling the movement of said plunger rod.
3. In a punch action, a notched punch stock, a punch head associated with said 20 punch stock, a gag, a stripper adapted for engagement with the notch in said punch stock, a rocker shaft, an arm carried by said

rocker shaft and connecting said stripper for actuating the latter during the movement of said rocker shaft, a plunger rod 25 for imparting a rocking movement to said rocker shaft, a rocker arm for controlling the movement of said plunger rod, and means for actuating said rocker arm.

4. In a punch action, a notched punch 30 stock, a punch head associated with said punch stock, a gag, a stripper movable with said gag and adapted for engagement with the notch in said punch stock, a rocker shaft, an arm carried by said rocker shaft and 35 connecting said stripper for actuating the latter during the movement of said rocker shaft, a plunger rod for imparting a rocking movement to said rocker shaft, a rocker arm for controlling the movement of said 40 plunger rod, and a cam for actuating said rocker arm.

In testimony whereof I affix my signature.
OTTO P. LEINHAUSER.
